UNITED STATES PATENT OFFICE.

LUDWIG SEGER, OF EDGEWATER, NEW JERSEY.

STEP AND WALL LADDER.

1,338,100.

Specification of Letters Patent. Patented Apr. 27, 1920.

Application filed April 11, 1918. Serial No. 227,895.

To all whom it may concern:

Be it known that I, LUDWIG SEGER, a citizen of the Republic of Switzerland, residing at Edgewater, county of Bergen, and State of New Jersey, have invented certain new and useful Improvements in Step and Wall Ladders, of which the following is a specification.

This invention relates to improvements in 10 combined step and wall ladders, and has as its special object the provision of a ladder which may be extended at full length, used in a folded position as a step ladder or further folded for storage.

15 A further object is to arrange the elements thereof so that they are firmly secured when in any of their adjusted positions, and finally to provide a novel form of joint connections comprised of integral elements, 20 secured to the adjoining ends of the ladder columns.

These and other like objects are attained by the novel construction and combination of parts hereinafter described and shown in 25 the accompanying drawings, forming a material part of this specification, and in which:-

Figure 1 is a side elevational view showing a ladder made in accordance with the 30 invention in a partially folded position.

Fig. 2 is a fragmentary side elevational view of the same, showing the columns in an extended position.

Fig. 3 is an enlarged fragmentary view of 35 the ladder as shown in a folded position in Fig. 1.

Fig. 4 is a fragmentary side elevational and sectional view showing the joints at the adjoining ends of the ladder columns, the 40 section being taken on line 4-4 of Fig. 3.

Fig. 5 is a transverse sectional view taken on line 5-5 of Fig. 4.

Fig. 6 is a vertical sectional view similar to Fig. 4 but showing a modified form of 45 joint cap.

Fig. 7 is a transverse sectional view taken on line 7-7 of Fig. 6.

Fig. 8 is a plan view of the developed blank of the joint caps.

50 Fig. 9 is a similar view showing a modified form of a cap plate.

Fig. 10 is a plan view showing a blank used as one of the hinge elements in the modified form, and

55 Fig. 11 is a plan view of the oppositely disposed hinge blank.

The ladder is comprised of four like columns arranged in pairs, as 10 and 12, and capable of being closed together in a compact manner when not in use. When the 60 device is used as a step ladder as indicated in Fig. 1, the columns 10 and 12 are spread at their lower ends and held in an adjusted position by links 14 and 15, containing slots, the same being engaged by screws 16 to the 65 outer rims of the ladder columns, the links being slotted longitudinally and engaged by bolts 17 provided with winged clamp nuts 18, the links being disposed upon each side of the ladder columns. Fixed rungs 19 extend from side to side between each pair of the columns 10 and 12 serving to brace the parts and also act as steps for the person using the ladder.

In the preferred form of cap, a blank, 75 shown fully developed in Fig. 8, is used, the same comprising a cap portion 20 having integrally formed lateral elements 22, adapted to be bent along the lines 21, downward over the upper ends of the ladder columns, 80 and joined with one of the portions 22 is a portion 24, bent along the line 23 at one end from the portion 22 and along the line 25, from the portion 26. The adjacent section 28, together with the section 24, is 85 adapted to be secured to the narrow edges of the ladder columns, and bent along the line 29 is the portion 30. These portions after bending are secured firmly to the ladder columns by means of bolts 32, passing 90 through the wood columns and openings 33, in the portions 22 and 30. Extending from the center portion 20 are strap like extensions 34 and 35, containing longitudinal slots 36 and 37, the material 36' and 37', when 95 curved in the manner indicated in Figs. 4 and 6, forming hinge elements, connected, when assembled, by the pins 38. Openings 40 are formed through the blanks receptive of the bolts 41. Other openings 42 are 100 formed through the elements 34 and 35 for the bolts 43.

Thus it will be seen, that the columns 10 and 12 are provided at their adjacent end edges with hinge joints connecting them, 105 and when, as shown in Fig. 2, another pin 38' is passed through the openings at the opposite edges of the ladder elements, they are held rigidly extended, the clamps 17 in the links 14 and 15 adding to the rigidity. 110

In the modification shown in Figs. 9, 10 and 11 a blank having plate portions 45

and lateral extensions 46 and 47 is provided, to the former of which is an extension 48, provided with holes through which the bolts may be passed. Separate eye elements, 50 and 52 form the hinges as shown in Figs. 10 and 11 and have openings 53 and 54, the remaining material being bent to form a circle and act as independent ears for the hinges.

10 From the foregoing it will be seen that a neat appearing, strong and serviceable ladder has been disclosed, capable of being extended and used against a wall or the like, or folded and used as a step ladder and 15 when not in use of being compactly folded for storage.

Having thus described my invention what I claim as new and desire to secure by Letters Patent, is,

20 A blank for forming a member of a ladder

hinge comprising a cap portion adapted to be used on the top end of a ladder stile, side portions adapted to engage the opposite sides of the ladder stile, a band like extension on one of said side portions adapted to be bent around the sides of the ladder stile, portions extending from the cap portion on both sides thereof, and slots immediately adjacent to the cap portion in the last mentioned portion, said portions being adapted to be bent down in engagement with the front and rear edges of the ladder stile with the portions between the slots curved to form eyes and with the slots adapted to receive the eyes on another hinge member, said eyes after being alined, being adapted to receive the pintle of the hinge.

In testimony whereof I have affixed my signature.

LUDWIG SEGER.
